UNITED STATES PATENT OFFICE.

RUDOLF KNIETSCH, OF LUDWIGSHAFEN, GERMANY, ASSIGNOR TO THE BADISCHE ANILIN & SODA FABRIK, OF LUDWIGSHAFEN, GERMANY, A CORPORATION OF GERMANY.

METHOD OF MAKING SULFURIC ANHYDRID.

SPECIFICATION forming part of Letters Patent No. 690,062, dated December 31, 1901.

Original application filed July 14, 1898, Serial No. 685,969. Divided and this application filed April 7, 1900. Serial No. 12,039. (No specimens.)

To all whom it may concern:

Be it known that I, RUDOLF KNIETSCH, doctor of philosophy, a subject of the King of Prussia, Emperor of Germany, residing at Ludwigshafen-on-the-Rhine, Kingdom of Bavaria, Germany, have invented certain new and useful Improvements in the Process for the Manufacture of Sulfuric Anhydrides, (which invention is divided out of my application for Letters

5 Patent filed July 14, 1898, Serial No. 685,969, which application had previously been divided, giving rise to the application filed August 18, 1899, Serial No. 727,636,) of which the following is a specification.

15 In my application, Serial No. 685,969, filed July 14, 1898, I described the apparatus and process described in this application. In the application, Serial No. 727,636, filed August 1899, I described a specific form of apparatus and claimed the specific apparatus and the process as carried out therewith. I file the present application as a division of the said application for the purpose of securing the specific claim on the said process.

25 In the accompanying drawings, Figure 1 is a vertical section of an apparatus containing a single contact-chamber, represented by a tube or pipe R. Fig. 2 is a vertical section of an apparatus containing a plurality of contact-chambers, represented by tubes or pipes R.

30 Referring first to Fig. 1, M represents a brickwork structure or an iron pipe. Within this a pipe R is fixed, leaving the passage S' between. This pipe R consists of two parts a and b, which have different functions and may differ from one another in length and diameter. Also either part can be replaced by a plurality of narrower pipes. The portion b of the pipe R is occupied by the contact substance, (indicated in the drawings by broken section lines,) and this is cooled by the cold air entering the passage S' at n. In the other part a of the pipe R the gases containing the sulfur dioxid which enter at O are heated to 35 the temperature necessary for the reaction. When commencing the operation, the whole apparatus is first raised to the temperature necessary for the reaction by heating by means of h h—say gas-flames. Then, when

40 gases rich in sulfur dioxid are used, after the reaction has once commenced further heating is unnecessary, because the air as it passes through the pipe M in contact with that part b of the pipe R in which the reaction is in progress in extracting the excess of heat due 45 to the reaction absorbs the heat and transfers sufficient heat to the other portion a to prevent a change of position of the reaction zone or the entire cessation of the reaction. The current of air can be regulated by means of 50 the updraft-openings L L, which are adjustable by the slides l l. It is regulated in such a way that the contact substance in b is constantly maintained at the most favorable temperature for the reaction. When the gases 55 contain but little sulfur dioxid, the air, which is somewhat heated by its cooling action on the contact substance, is further heated by suitable means h' h', (such as gas-flames,) so that the gases in flowing through part a receive 60 a greater increment of heat. When the gases are still poorer in sulfur dioxid, it may be necessary to continually heat to some extent the current of air flowing in through n, either by means of the gas-flames at h h or in 65 some other way. The gases containing the sulfuric anhydrid issuing from the contact-chamber b leave the apparatus by the pipe C and are worked up in any suitable way.

70 The apparatus represented in Fig. 2 is made up of a plurality of contact-tubes R R, which are in connection with one another by means of the two tube-plates W W and the covers D D' above and below. In other respects it 75 resembles Fig. 1.

80 It will now be manifest that in the operation above described there are two independent currents of gas. One of them—the mixture containing sulfur dioxid and oxygen—passes through the pipe R and is converted. 85 The other current, differently constituted, passes through the passage adjoining the pipe R, but does not enter the contact material, and performs the function of transferring the excess of heat due to the reaction from the 90 part b of the tube R to the part a thereof.

I claim—

1. The herein-described process of making

sulfuric anhydrid which consists in passing a gas containing sulfur dioxide and oxygen through a contact substance while removing excess of heat due to the reaction from the 5 contents of the contact-chamber by means of a current of fluid which does not enter the contact material, substantially as described.

2. The herein-described process of making sulfuric anhydrid which consists in passing 10 a gas containing sulfur dioxide and oxygen through a contact substance while removing excess of heat due to the reaction from the contents of the contact-chamber by means of a current of air, substantially as described.

15 3. The herein-described process of making sulfuric anhydrid which consists in passing a gas containing sulfur dioxide and oxygen through a contact substance while removing excess of heat due to the reaction from the 20 contents of the contact-chamber by means of

a current of fluid differently constituted from the said gas, substantially as described.

4. The herein-described process of making sulfuric anhydrid which consists in passing a current of gas containing sulfur dioxide and 25 oxygen through a contact substance while transferring excess of heat due to the reaction from the contact substance to said chamber by means of a second current of fluid differently constituted from and flowing in a direction inversely to that of the first-named current, substantially as described.

In testimony whereof I have hereunto set my hand in the presence of two subscribing witnesses.

RUDOLF KNIETSCH.
